UNITED STATES PATENT OFFICE.

EVARTS G. LOOMIS, OF NEWARK, NEW JERSEY, ASSIGNOR TO ST. MUNGO MANUFACTURING COMPANY OF AMERICA, OF NEWARK, NEW JERSEY, A CORPORATION OF NEW JERSEY.

BALL-WINDING MACHINE.

Application filed June 7, 1922. Serial No. 566,468.

To all whom it may concern:

Be it known that I, EVARTS G. LOOMIS, a citizen of the United States, and a resident of Newark, county of Essex, and State of New Jersey, have invented certain new and useful Improvements in Ball-Winding Machines, of which the following is a specification.

My invention relates to a machine for winding balls and is intended particularly for winding golf ball centers.

An object of the invention is the provision of a machine which is adapted automatically to wind balls with a distribution of thread that will give a smooth, neat, spherical finish and will knit well with the cover of the ball and yet be free from protuberances that weaken the cover of the ball.

Fig. 1 shows in part sectional elevation 20 a machine embodying my invention;

Fig. 2 is a plan view of the machine of Fig. 1;

Fig. 3 is a section taken substantially on the line 3—3 of Fig. 1;

Fig. 4 is a section through one of the heads of Fig. 1, the section being taken substantially on the line 4—4 of said figure; and

Fig. 5 illustrates a partially wound core 30 wound in my improved machine.

Referring to the drawings in detail, 1 designates the frame of the machine which is provided with bearings 2 and 3 in which is supported a longitudinally extending drive shaft 4, this shaft carrying driving pulley 5 and loose pulley 6.

Mounted on the drive shaft adjacent the bearing 2 is a broad-faced drive gear 7 meshing with a narrow-faced slidable gear 8 carried by a stub shaft 9 to which it is pinned or otherwise rigidly secured. The stub shaft 9 is mounted in bearings 10 and 11, the latter being provided by a standard 40 12 supported by rods 13 extending lengthwise of the machine. The stub shaft 9 carries one of the rotary heads 14 by which a core designated 15 is held in place in the machine, this head comprising a pair of bevelled independently rotatable rollers 16

adapted to engage the surface of the core 50 during the winding operation. The shaft 9 being movable longitudinally, permits the head 14 to recede to the left as viewed in Fig. 1 so as to accommodate itself to the gradual increasing diameter of the core, the gear 8 sliding along the face of the gear 7.

The drive shaft 4 also carries a gear 17 which is of the same size as the gear 7 and meshes with a gear 18 carried by a hollow shaft 19 in alignment with the stub shaft 9. The gear 18 is of the same size as the gear 8. A sleeve 20 mounted in a standard 21 supported by the rod 13 provides a bearing for the hollow shaft 19. Screwed on the outer reduced end of this shaft is a head 22 adapted to engage the core 15 on the opposite side to the head 14 already referred to.

The heads 14 and 22 by reason of the gears 7, 17 and 8, 18 being of the same size rotate at the same speed. On the head 22 I provide 70 a yoke 23 which carries a pair of elongated rollers 24 and 25. The roller 24 is mounted on a squared shaft 26 supported in the yoke 23 while the roller 25 is slidably mounted on a similar shaft 27. The squared shafts 75 26 and 27 also support racks 28 and 29 respectively provided for the purpose of reciprocating or sliding the rollers 24 and 25 longitudinally and in opposed directions.

One side of the yoke 23 receives and supports a small stud 30 on which is mounted a straight-faced gear 31 meshing with gears 32 and 33 carried on the ends of the shafts 26 and 27 respectively. As so far described the head 22 is adapted to be rotated by the 80 hollow shaft 19 carrying the rollers 24 and 25 along with it, these rollers also having a reciprocatory movement as well as a rotary movement about their individual axes.

Attached to what may be termed the hub 90 of the head 22 is a stud 34 carrying a straight-faced gear 35 meshing with the gear 31 already referred to. This stud also carries a bevelled gear 36 meshing with a bevelled gear 37 mounted on a sleeve 38 carried by 95 the shaft 19. The bevelled gear 36 is provided with a friction brake 39 the purpose of which will be pointed out hereinafter.

Rigidly attached to the hub of the bevelled gear 37 is a sleeve 40 and surrounding this sleeve and keyed to it is a ring 41 with which a brake 39' is adapted to cooperate. The 5 brake 39' is controlled by mechanism best seen in Fig. 3.

From this figure it will be seen that the standard 21 supports a pivoted arm 43 carrying a roller 44 at its upper end adapted to be 10 operated on by a cam 45 mounted on the shaft 4 and provided with detents 46 and 47 which actually engage the roller. The arm 43 is provided with a short rod 48 attached to a brake-controlling link 49, this link being attached to the brake band comprising a part of the brake 39' already referred to. The brake link 49 is provided 15 with an ear or lug 50 for receiving one end of a coil spring 51, the other end of which is secured to a fixed ear 52. It will be seen 20 that when the roller 44 is brought into engagement with either of the detents 46 or 47 of the cam 45 the arm 43 will be rocked about its pivot so as to apply the brake 39' 25 which is normally released by the tension spring 51.

Extending through the hollow shaft 19 is a small shaft 53 carrying at its left hand end as viewed in Fig. 1 a pinion 54 which as 30 will be seen from Fig. 3 engages the racks 28 and 29 with which the head 22 is provided. The hole in shaft 19 is reduced at the end adjacent the head 22 to form an interior shoulder providing an abutment for 35 a collar 55 carried on the rod 53. The shaft 19 at its bearing in the frame 1 receives a sliding cam sleeve 56 keyed to and rotated by hollow shaft 19 but free to slide longitudinally therein and provided with cam 40 slots 57. The rod 53 already referred to is provided with a pair of rollers 59 which ride in the cam slots 57.

Pivoted on the frame 1 is a lever 60 carrying a roller 61 at its extreme end and also 45 a swivel block 60'. The motion of lever 60 may be limited by the nut 100 on stud 96', Fig. 2. The roller 61 is adapted to cooperate with a cam 62 carried by a large gear 63 which is supported on a longitudinally 50 movable shaft 64 mounted in bearings in the standard 12 and the frame 1. The roller 61 is maintained in engagement with the face of the cam 62 by means of a spring 65, one end of which abuts the collar 55 on the 55 shaft 53, the other end engaging the shoulder 66 on the sleeve 56. The gear 63 is driven by a broad-faced pinion 67 carried at the extreme right hand end of the drive shaft 4.

Operatively connected to the stub shaft 9 60 is an arm 68 pivotally mounted on the standard 12, this same arm also being connected to the end of the shaft 64 carrying the gear 63. It will be seen therefore that the head 14 and the gear 63 are in effect connected to 65 each other by the rod 64 and the arm 68 so

that as the head 14 recedes due to the increasing diameter of the core the gear 63 will be given a corresponding movement. At the lower end of the member or arm 68 I attach a cable 69 which may be operated by 70 a foot pedal and by which the head 14 may be moved away from the core 15 so that the latter may be removed from the machine at the completion of the winding operation.

In order that the thread 70 may always 75 be properly led to the core 15 I provide arms 85 and 86, the latter carrying tape guiding rollers 87 and 88. These arms are mounted on a vertically extending rod 89. Attached to the arm 85 is a rod 90 carrying a roller 91 cooperating with a cam 92 carried by 80 the gear 63.

Having now described the construction of my improved machine I will proceed to describe a cycle of operation thereof in the 85 process of winding a core as indicated diagrammatically in Fig. 5. Assuming that the parts of the machine are in position wherein the sleeve 56 is in its full retracted position, i. e., in engagement with the low part of the 90 cam 62 and that the brake lever 43 or rather the roller 44 carried thereby is out of engagement with the detents 46 or 47 being held in this position by the spring 93.

I may here mention before proceeding further with the operation of the machine, that 95 the brake-controlling lever 43 is adapted to be controlled in part by a shaft 94 which extends parallel to the drive shaft 4 and is slidable in the standard 21 and frame 1 and 100 controlled by a pair of cams 94^a and 94^b mounted on the large gear 63. These two cams as will be seen from Fig. 3 are spaced 180° apart.

The driving gears 7 and 17 which have 105 already been referred to are of the same diameter so as to drive the heads 14 and 22 at the same speed. The ratio between the pinion 67 and the large gear 63 in this particular machine is twenty-one to one. The 110 core 15, after the thread has been attached thereto may be inserted in the machine by moving the head 14 away from the head 23 by operation of the cable 69. The thread 70 is then led over the top of the roller 88 115 and the machine is now ready for operation, the heads 14 and 22 being driven in the same direction, i. e., in a direction away from the observer as viewed in Fig. 2 and the core 15 being rotated about a horizontal 120 axis parallel to the longitudinal axis of the machine. It will be assumed at this time that the cams 94^a and 94^b are both out of engagement with the end of the rod 94 so that the brake 39' is in released position. This being so the bevelled gear 37 is free to 125 rotate with the shaft 19 and hence no rotary motion is imparted to the bevelled gear 36 nor the racks 28 and 29, nor are the rollers 24 and 25 rotated on their individual axes. 130

As the ball is rotated on its horizontal axis by the heads 14 and 22 from the position shown, the roller 91 commences to travel down the cam surface 92 permitting 5 the rod 90 and thread guide levers 85 and 86 to move to the right under the action of the spring 58, Fig. 2. Thus the line of travel of the thread is moved to the right by means of the motion of the roller 88. These two 10 motions will obviously cause the thread to be wrapped in the form of a spiral or helix on the surface of the ball and in this particular construction ten and one-half turns are thus given to the ball in this manner, 15 when the horizontal axis of the ball will be shifted as will be later explained and then another similar helical winding of ten and one-half wraps will be laid on the ball but in this case from the right to the left and 20 so on alternately. This form of winding is clearly indicated in Fig. 5. At the instant of operation shown in the figures the cam 94^a will have been brought into position to engage the end of the rod 94 to 25 force the lever 43 into position to bring its roller 44 into engagement with the cam 46 or 47 as the case may be to apply the brake 39' to the bevelled gear 37 holding the same against rotation.

30 With the gear 37 stationary and the head 22 still rotating it will be at once apparent that the bevelled gear 36 will be rotated on its stud 34 to rotate the small gears 32 and 33 to cause the rollers 24 and 25 to rotate 35 in the direction of the arrow on the roller 24 of Fig. 1. This motion of the rollers 24 and 25 will impart a movement to the core 15 in a clockwise direction about a vertical axis as viewed in Fig. 2 and inasmuch as 40 the ball at this time is rotating about an axis parallel to the longitudinal axis of the machine the last wrap on the core and which I will designate 97 is brought across the wraps 96 as indicated in Fig. 5. By the 45 time the last wrap of thread has reached the position shown in Fig. 5 on the core 15 the cam 46 or 47 as the case may be will have ridden away from the brake lever 43 and the latter will have been restored to 50 its original position by the spring 93. The brake on the bevelled gear 37 now being released, the motion of the core about a vertical axis due to rotation of the rollers 24 and 25 on their individual axes will cease.

55 However, as the machine operates the receding surface of the cam 62 will allow the spring 65 to act upon the end of the sleeve 56 pushing the latter to the right and by reason of the cam slot 57 the shaft 53 and 60 pinion 54 will be rotated in the opposite direction of rotation of the head 22 causing the roller 24 to move endwise vertically as viewed in Fig. 1 and the roller 25 to move endwise in the opposite direction. This motion of the rollers 24 and 25 will rotate

the core about the same horizontal axis about which it is turning but will change the original vertical axis of the ball in relation to the axes of the rollers 24 and 25 so that the former pole or point of crossing of 70 the windings will be shifted about 90° more or less in relation to the winding head 22.

It will be evident that if the thread is fed to the core under tension as it actually is in practice, pull of the tensioned thread will 75 tend to assist this spring operated motion.

As the thread is applied to the core the diameter of the core of course constantly increases and in order to take care of this increase in diameter and maintain the conditions necessary to produce a spherical ball the gear 63 on which the controlling cams are mounted is given an endwise motion in line with the axis of rotation as will be seen in Fig. 5 and as has been explained. When 80 the smallest center or core to be wound is first inserted between the winding heads the gear 63 is in its extreme right hand position and the lever 60 is limited in its travel by the nut 100 so that at the time the roller 61 90 is held out of contact with the cam 62 and by this means the travel of the cam sleeve 56 and the corresponding endwise motions of the rollers 24 and 25 are reduced to compensate for the smaller circumference of the 95 core. As the core increases in diameter it will be clear that there will be less lost motion of the lever 60 and a corresponding increase in the endwise travel of the rollers 24 and 25 so that for all sizes this motion will 100 be proportioned to give an approximately equal angular displacement of the ball axis between each twisting motion.

Also as the core increases in diameter the shaft 94 will be given a greater movement 105 to the left by the cams 94^a and 94^b and consequently the roller 44 will engage a correspondingly wider portion of the tapered lobes 46 and 47 of the cam 45 and hence a relatively greater degree of rotation will be 110 given to the rollers 24 and 25 to compensate for the increased circumference of the core 15 so that its correct angular displacement will be maintained.

Moreover this endwise motion of the gear 115 63 will act to vary the location of the arc of travel of the thread guide lever 86 as will be evident, causing it to shift to the left to compensate for the change in position of the center of the core to the left as the core is 120 increased in size.

It will be seen from the foregoing that I have provided a machine in which the heads 14 and 22 which hold the core are rotated on a common axis, the thread guiding rollers 86 and 87 guiding the thread in a direction which is parallel to the axis of rotation of the heads 14 and 22 and that by providing means for moving the rollers 14 and 22 endwise but in opposed directions and for 125 130

rotating these rollers on their individual axes the axis of rotation of the ball in relation to the axis of rotation of the heads is intermittently changed.

5 It will be seen also that the core is rotated for a predetermined number of times about a given fixed axis, to-wit: an axis parallel to the longitudinal axis of the machine and that simultaneously the plane of winding of the thread 70 is moved in a direction parallel to said axis, the intermittent rotation of the rollers 24 and 25 on their individual axes intermittently rotating the core on a secondary axis which is at right angles 10 to the first fixed axis and that by imparting an endwise motion to the rollers 24 and 25 in opposite directions intermittently I impart a third rotative motion to the core about the fixed axis above mentioned, the 15 motion imparted to the core by this intermittent movement of the rollers 24 and 25, however, being alternated so as to vary the location of the poles 99 on the surface of the core with respect to each other and to apply 20 the thread to the ball in such a way that there is the least possible tendency of the thread to slip off during the winding operation, the result being a firm neat winding 25 and a substantially spherical core with a 30 substantially smooth surface.

While I have described the precise details of a machine embodying my invention it is to be understood that these details may be varied or modified within the scope of my 35 invention.

I claim:

1. The method of winding a sphere which 40 method consists in rotating the sphere a predetermined number of times about a predetermined fixed axis while simultaneously moving the plane of winding of the thread in a direction parallel to said axis to cause the thread to traverse the ball, intermittently 45 rotating the sphere on secondary axes at an angle to said fixed axis and simultaneously imparting a third rotary motion to the sphere alternately in the same and in an opposite direction to the motion of the sphere about the predetermined fixed axis.

50 2. In a ball winding machine the combination of a pair of heads rotatable on a common axis for holding and rotating a ball to be wound, means for causing the thread to traverse said ball in a direction parallel to said axis of rotation of said heads and means for intermittently changing the axis of the ball in relation to the axis of the head.

55 3. In a ball winding machine the combination of means for rotating a ball a predetermined number of times about an axis, thread-controlling means for simultaneously causing the thread to traverse the ball in a direction parallel to said axis and means for intermittently changing the axis of rotation 60 of the ball.

4. In a ball winding machine, means for rotating the ball to be wound a predetermined number of times about a given fixed axis, means for simultaneously causing the thread to traverse the ball in a direction 70 parallel to said axis, and means for intermittently rotating the ball on a second axis at right angles to the said fixed axis.

5. In a ball winding machine, mechanism 75 for rotating a ball to be wound a predetermined number of times about a given fixed axis while simultaneously causing the thread to traverse the ball in a direction parallel to said axis, mechanism for intermittently rotating the ball on secondary axes at right 80 angles to said fixed axis, and means for superposing a third rotating motion on the first mentioned axis but alternately in the same and opposite directions to the first motion to change each time the position of the 85 secondary axes in relation to each other.

6. A ball winding machine comprising 90 two rotatable heads for holding a ball, one head being provided with means for changing the winding axis of said ball, means for moving one head in the direction of its axis of rotation due to the increasing diameter of the ball, this means acting to vary the motion of the mechanism for changing the axis 95 of the ball to compensate for the increasing circumference of the ball.

7. In a ball winding machine, the combination of two rotatable oppositely disposed heads for receiving a core to be wound, 100 means for leading thread to said core, mechanism for imparting rotary movement to a core held in said heads and to cause the thread to be applied thereto helically and means for periodically changing the direction of rotation of the core to vary the location of the helical wraps of thread thereon. 105

8. In a ball winding machine, the combination of a pair of rotatable heads for holding and rotating a core to be wound, means 110 for causing the thread to traverse said core in a direction parallel to the axis of rotation of said heads, one of said heads comprising a pair of elongated rollers, means for periodically moving said rollers longitudinally and in opposite directions simultaneously, and mechanism for imparting a 115 rotary motion to said rollers about their individual axes.

9. In a ball winding machine, the combination of a pair of rotatable heads for receiving and holding a core to be wound, a pair of elongated rollers carried by one head directly engaging the surface of said core, mechanism for effecting a lengthwise movement of said rollers in opposite directions and mechanism for effecting rotation of said elongated rollers on their individual axes at the end of their longitudinal movement to effect a change in the axis of rotation of the 120 core whereby sets of wraps of thread will 125

be applied to the core at an angle to each other.

10. In a ball winding machine, the combination of a pair of rotatable heads for receiving and holding a core to be wound, a pair of elongated rollers carried by one head and adapted to engage the surface of the core being wound, means for effecting a longitudinal movement of said elongated rollers in opposed directions simultaneously, means for rotating said elongated rollers on their individual axes at the end of their longitudinal movement to effect a change in the direction of rotation of said core to bring the core into position to receive a second set of wraps overlying but at an angle to the first set of wraps and cam mechanism for controlling the cross-over of each set of wraps whereby the location of this point on the periphery of the core will be varied.

11. In a ball winding machine, the combination of a pair of rotatable heads, a pair of freely movable, independently rotatable rollers carried by one head, a pair of elongated rollers carried by the other head, all of said heads being located so as to engage and hold a core in said heads, rack and pinion mechanism for effecting longitudinal movement of said elongated rollers, cam mechanism for effecting operation of said rack and pinion mechanism, gearing for effecting rotation of said elongated rollers on their individual axes and cam-controlled brake mechanism for controlling said gearing.

12. In a ball winding machine, the combination of a pair of heads for receiving and holding a core to be wound, a pair of elongated rollers carried by one head and adapted to engage the periphery of the core, a hollow shaft carrying the last-mentioned head, a rod extending through said shaft and carrying a pinion, a pair of racks operatively connected to said pinion and adapted to effect a longitudinal movement of said elongated rollers and cam mechanism for effecting a rotation of the shaft carrying said pinion in one direction throughout a portion of the movement of said cam mechanism and in the opposite direction throughout the remaining portion of the movement of said cam mechanism.

13. In a ball winding machine, the combination of a pair of rotatable heads for receiving and holding a core to be wound, gearing for rotating said heads in the same direction and at the same speed simultaneously, a hollow shaft carrying one head, a pair of elongated rollers carried by said head and adapted to engage the periphery of the core being wound, a shaft extending through said hollow shaft, a pinion carried thereby a pair of racks connected to said rollers and adapted to be actuated by said pinion, a sleeve carried by said pinion-carry-

ing shaft, said sleeve being provided with a cam slot cooperating with a cam on the pinion-carrying shaft, and cam mechanism for effecting a longitudinal movement of said sleeve to cause the pinion-carrying shaft to be rotated first in one direction and then the opposite direction to effect a longitudinal movement of said rollers simultaneously but in opposed directions.

14. In a ball winding machine, the combination of a pair of rotatable heads adapted to receive a core to be wound, means for effecting a movement of one of said heads in the direction of its axis of rotation as the diameter of the core being wound increases, a pair of elongated rollers carried by the other head and adapted to engage the surface of the core being wound, mechanism for effecting a lengthwise motion of said elongated rollers simultaneously and in opposed directions, said mechanism automatically compensating for the movement of one of said heads in the direction of its axis of rotation.

15. In a ball winding machine, the combination of a pair of rotatable heads adapted to receive and hold a core to be wound, means for automatically effecting a movement of one of said heads in the direction of its axis of rotation as the diameter of the core increases, a pair of elongated rollers carried by the other head, rack and pinion mechanism for effecting a lengthwise motion of said elongated rollers simultaneously and in opposed directions, cam mechanism for controlling the operation of said rack and pinion mechanism, gearing carried by the head on which said elongated rollers are mounted for effecting rotation of said elongated rollers on their individual axes, mechanism for controlling the operation of said gearing, mechanism for controlling said brake, and a gear for carrying the last-mentioned mechanism and the mechanism for controlling the operation of the said rack and pinion, said gear being moved in the direction of its axis of rotation as the diameter of the article being wound increases.

16. In a ball winding machine, the combination of a pair of rotatable heads for receiving and rotating a core to be wound, one head being movable automatically in the direction of its axis of rotation as the diameter of the core increases, a gear, a rod connecting said gear to said last-mentioned head whereby said gear and head will be moved simultaneously, a pair of rollers carried by the other of said heads, gearing for effecting a predetermined movement of said rollers and mechanism controlled by said movable gear for controlling the operation of said gearing.

17. In a ball winding machine, the combination of a pair of rotatable heads for receiving and rotating a core to be wound, a

pair of elongated rollers carried by one of said heads, a rotatable hollow shaft for supporting the head last mentioned, a bevelled gear mounted on said hollow shaft, a bevelled gear meshing therewith and carried by said head and cam-controlled mechanism cooperating with the first-mentioned bevelled gear to effect rotation of said elongated rollers at predetermined intervals on their individual axes.

This specification signed this 6th day of June, 1922.

EVARTS G. LOOMIS.
